UNITED STATES PATENT OFFICE.

WILLIAM R. TAYLOR, OF CLARENDON, VIRGINIA.

HYDRAULIC CAISSON.

Application filed May 18, 1927. Serial No. 191,727.

This invention relates to the construction of hydraulic caissons and like structures for laying foundation work, particularly in sand and mud bottoms.

5 In the placing of caissons and the like which are generally floated to the work and lowered by their own or artificial weight, resistance is offered to the sinking of the structure by the adhesion of the sand and mud 10 bottom against the sides thereof. It has been proposed to break up this adhesion by the introduction of various forms of jets of air or water under pressure thru the sides of the structure to facilitate the passage of the structure into the bottom. All of the devices of 15 this character heretofore provided with jets suitably positioned for advantageous results are both cumbersome and expensive in application, while pressure supply lines to the jets 20 are difficult in maintenance particularly with large and remote installations.

One object of my invention is to provide a caisson or like structure which may be readily located and sunk into position without the provision of expensive jet installations.

A further object of my invention is to provide a structure of the character above described, which is simple and inexpensive in 30 construction, and which effectively acts to dissipate the resistance offered to its sinking caused by adhesion of the sand or mud bottoms to the sides thereof.

A further object is to provide a caisson or 35 like structure whose rate of sinking and level during such sinking may be effectively controlled.

Other objects will be in part obvious from the annexed drawing and in part indicated 40 from the following analysis of the invention, in which reference is made to the accompanying drawings illustrating one embodiment of my idea.

In the drawings—

45 Fig. 1 is a vertical section taken along lines 1—1 of Fig. 2;

Fig. 2 is a plan of a complete rectangular caisson;

50 Fig. 3 is a fragmentary view of the wall construction showing water openings or ori-fices;

Fig. 4 is a detail of the cutting edge of the caisson;

55 Fig. 5 is a fragmentary section thru the walls and channel members of the caisson;

Fig. 6 is a detail of a channel plate provided with a water passage therethru;

Fig. 7 is a detail in section showing a preferred form of cutting edge construction;

Fig. 8 is a detail of a portion of the plates 60 at the water orifice; and

Fig. 9 is a detail in perspective of the plates and orifice.

Referring now to the drawings, there is disclosed for purposes of illustration a caisson of rectangular shape, but it will be understood that the general shape of the structure is immaterial and depends on the foundation sought to be laid and the particular place and conditions under which it is to be 65 used. The caisson comprises inner and outer sections, the outer section being formed of walls 1 and 2, and the inner section being formed of walls 3 and 4, the sections being spaced by a chamber 7 therebetween. The 70 walls 1 and 2 are separated by channel plates 5 to form a water compartment 6 therebetween. The walls 3 and 4 are similarly spaced by channel plates 5 and form a second water compartment 6a. The said channel 75 plates are provided with openings 9 to permit free passage of the water throughout the respective water compartments.

In the chamber 7, it is proposed to place concrete, rock or other materials, to accelerate 80 the sinking of the caisson to the proper level, and it will be understood that this filling may either remain therein or be removed, depending upon the particular installation.

The foundation is laid in the central chamber 8, from which the water may be pumped or otherwise removed. The bottom portions 90 of the inner and outer sections incline towards each other to form a cutting edge, the walls 1 and 4 being fastened to an angle iron 95 10 of V-shape, to which the channel plates 5 are also fastened as by bolts 17. To provide adequate strength to the structure, as well as a ready connection between the angle 10 and channel plates 5, I provide gusset plates 11 100 bolted to said parts as indicated at 17 and which are provided with holes 12 for the passage of water therethru. A longitudinally extending plate 18 is provided between walls 2 and 3 to form a bottom for the weight compartment 7.

The walls 1 and 4 are formed of plates lapped upwardly (see Figs. 8 and 9) and a seam 14 is consequently formed along the lap. At intervals along the seam, I provide 110

orifices 13 formed by bulging out portions of the lap as at 15, by suitable means such as a special tool. The said orifices are longer than they are wide, and are arranged in 5 staggered relation, to thus direct a flat jet water upwardly along the walls. By reference to Fig. 1, the caisson structure extends above the water level, and sufficient water is maintained in the compartments 6 and 6^a 10 to provide a pressure head therein acting to force water thru the orifices. It will be understood that the walls of the structure are adapted to be built upwardly as it sinks, or when necessary, by adding extra plates 15 and framework.

By reason of varying bottom structures or conditions thereof, it has been found that one end of the caisson may sink faster and thus reach a different level from the other 20 end thereof. To obviate this undesirable feature, I may place solid or imperforate channels 16 at intervals between the walls 1, 2 and 3, 4 and in the water compartments 6 and 6^a, the channels being fastened to the angle 25 10 and gusset plates 11, thus forming sub-compartments in the main water compartments 6 and 6^a. If one end of the caisson is found to be sinking faster or to a greater depth than the other end, the supply of water 30 to the said compartments of the lower level is cut off and the jets thru orifices 13 of those compartments are discontinued until the caisson has sunk level.

Water is supplied to the compartments 6 35 and 6^a and to the individual sub-compartments therein by any suitable means such as a supply line delivering to a plurality of funnels 22, of which one is shown (Figs. 1 and 2), and which fit over the tops of the 40 walls and may overlie the plates 5 or 16, depending on the sub-compartment sought to be supplied with water.

It will be evident from the above description that, as the caisson sinks into the bottom, the upwardly directed jets issuing thru orifice 13 serve as a lubricant and also assist in breaking the adhesion of the mud or sand to the sides of the structure. The construction of the caisson generally and orifices therein being simple and practical, increased economy and greater utility results. 50

It will be seen that the several objects of the invention are achieved and other advantageous results attained. As many changes 55 could be made in carrying out the above invention, it is intended that all matter contained in the above description or shown in the accompanying drawing shall be interpreted as illustrative and not in a limiting 60 sense.

I claim:—

1. A caisson comprising inner and outer sections spaced to provide a weight compartment therebetween, each of said sections comprising outer and inner walls formed of lon-

gitudinally extending plates and providing water compartments between the walls of the respective sections, and means formed on the relatively outermost and innermost walls permitting and causing jets of water from the water compartments to be directed upwardly along said walls. 70

2. A caisson comprising inner and outer sections spaced to provide a weight compartment therebetween, each of said sections comprising outer and inner walls formed of longitudinally extending plates and providing water compartments between the walls of the respective sections, the plates of the relatively outermost and innermost walls being overlapped upwardly to form a seam, and means formed in the seams to direct a plurality of jets of water from the water compartments upwardly along said walls. 75

3. A caisson comprising inner and outer sections spaced to provide a weight compartment therebetween, each of said sections comprising outer and inner walls formed of longitudinally extending plates and providing water compartments between the walls of the respective sections, the plates of the relatively outermost and innermost walls being overlapped upwardly to form a seam, bulges formed at intervals along the seams to provide a plurality of orifices adapted to direct 80 a plurality of jets of water from the water compartments upwardly along said walls. 85

4. A caisson comprising inner and outer sections spaced to provide a weight compartment therebetween, each of said sections comprising outer and inner walls formed of longitudinally extending plates and providing water compartments between the walls of the respective sections, the plates of the relatively outermost and innermost walls being overlapped upwardly to form a seam, bulges formed at intervals along the seams to provide a plurality of orifices adapted to direct 90 a plurality of jets of water from the water compartments upwardly along said walls. 95

5. A caisson comprising inner and outer sections spaced to provide a weight compartment therebetween, each of said sections comprising outer and inner walls formed of longitudinally extending plates, and channel members extending between the walls of the respective sections to form water compartments, and having openings formed therein to permit passage of water therethru. 105

6. A caisson comprising inner and outer sections spaced to provide a weight compartment therebetween, each of said sections comprising outer and inner walls formed of longitudinally extending plates, and imperforate channel members extending at intervals between the walls of the respective sections and providing a plurality of water compartments in each of said sections. 125

7. A caisson comprising inner and outer 130

sections spaced to provide a weight compartment therebetween, each of said sections comprising outer and inner walls formed of longitudinally extending plates, imperforate channel members extending at intervals between the walls of the respective sections and providing a plurality of water compartments in each of said sections, and channel members arranged between said walls and spaced at intervals in said compartments and having openings to permit the passage of water therethru.

8. A caisson comprising inner and outer sections spaced to provide a weight compartment therebetween, each of said sections comprising outer and inner walls formed of longitudinally extending plates, channel members extending between said walls and forming water compartments in said sections, the plates of the relatively outermost and innermost walls being overlapped upwardly to form a seam therebetween, and means formed in the seams to direct a plurality of jets of water from the water compartments upwardly along said walls.

9. A caisson comprising inner and outer sections spaced to provide a compartment

therebetween, each of said sections comprising outer and inner walls formed of longitudinally extending plates, channel members extending between said walls and forming water compartments in said sections, the plates of the relatively outermost and innermost walls being overlapped upwardly to form a seam therebetween, and bulges formed at intervals along the seams to provide a plurality of orifices adapted to direct jets of water from said water compartments upwardly along said walls.

10. A wall for caissons or like structures comprising a series of longitudinally extending plates in partially overlapped relation, and bulges formed in the plates at intervals along the seams resulting from such overlapping to provide orifices for the emission of water retained by the wall.

11. A wall for caissons or like structures comprising a series of longitudinally extending plates in partially overlapped relation, and bulges formed in the plates at intervals along the seams resulting from such overlapping and in staggered relation to the bulges of adjacent seams.

WILLIAM R. TAYLOR.
